pany, St. Louis, Mo., a corporation of Dela-
ware

No Drawing. Application March 3, 1936,
Serial No. 66,896

8 Claims. (Cl. 196—36)

This invention relates to the refining of petroleum distillates for motor fuel purposes which are rich in impurities that impart color and odor, or are productive of gum. In addition, the invention contemplates a treatment whereby the antiknock value of the fuel is increased and the susceptibility to tetra ethyl lead is improved.

The petroleum fractions which may be treated according to the present invention are generally made by cracking relatively higher boiling petroleum products. However, they may also be produced by polymerizing lower boiling products. In either case the raw material having the desired boiling range for motor fuel purposes may be malodorous, off color, rich in gum forming constituents, and may frequently contain sulfur in objectionable amounts.

Various methods are now used to refine this, so called, raw gasoline to render it suitable for motor fuel purposes. In most instances several successive treatments are necessary in order that a product having the desired properties is ultimately obtained. One common procedure for removing the sulfur and gum forming constituents consists in washing the raw gasoline with sulfuric acid, subsequently with water, and thereafter with alkali to remove residual acidity. The product is then redistilled.

An alternative procedure consists in contacting the raw gasoline with active clay, whereby the gum forming constituents are partially separated. It is generally necessary to follow the clay treatment with a doctor treatment, which is calculated to remove objectionable odors, especially those attributable to the presence of sulfur impurities. Not infrequently this is also necessary in the case of acid treated gasoline. With either method of treatment gum inhibitors are commonly added to the gasoline, especially if the gasoline is apt to be stored for a considerable period of time before use.

Present day practices share many objectionable features. Thus, for example, the sulfuric acid treatment is not selective. In other words, it not only combines with the gum forming constituents, but also with the desirable olefinic components of a raw gasoline, thereby reducing the yield of gasoline and impairing the antiknock quality of the product. A reduction in the amount of sulfuric acid employed to reduce the loss of desirable motor fuel constituents is possible only to a limited extent inasmuch as a substantial amount of sulfuric acid is necessary, especially where a reduction in the sulfur content of the gasoline is desired. Because it is not

possible to improve gasoline with regard to the presence of sulfur and gum forming constituents without materially reducing the yield and antiknock properties of the fuel, refiners indulge in a compromise between bum and sulfur impurities on the one hand and cost of refining reagents and sacrifice in yield on the other. Thus, for example, a treatment with sulfuric acid may lower the antiknock value of a fuel 5 to 15 points if a substantially gum free and low sulfur product is desired. At the same time ten per cent or more of the fuel may be lost as sludge.

The clay treatment avoids certain objectionable features of the sulfuric acid treatment, but has no effect whatever on sulfur. Furthermore, the clay treatment does not eliminate the gum forming constituents entirely, but rather eliminates only part of these to give temporary stability and necessitates the use of so-called gum inhibitors in the finished gasoline product to attain relatively permanent stability.

Whether one employs the clay or acid treatments, it is generally necessary, in order to obtain a gasoline product having the required color stability and freedom from odor, to subject it to a sweetening treatment. This treatment requires the use of additional chemical reagents and necessitates several additional steps in the refining operation.

In the usual sweetening reaction, the mercaptans are transformed quantitatively to disulfides. This is usually accomplished with the aid of a source of oxygen. The presence of small quantities of disulfides contributes materially to poor color stability, poor susceptibility to the effect of tetra ethyl lead, poor susceptibility to gum inhibitors, and to an actual loss in octane number. In addition, the presence of free sulfur, which is normally required in excess to assure complete conversion of the mercaptides to disulfides, impairs color stability and promotes corrosion. The effect of oxygen on cracked gasolines is rather well known, and the resulting peroxidation exerts a detrimental effect on inhibitor susceptibility and antiknock properties, (see "Oil and Gas Journal" of February 6, 1936, page 28 et seq.).

According to the present invention, the raw gasoline is treated in a manner described more fully hereinafter, whereby the following advantages and improvements over the prior processes are attained:

1. Practically complete and selective removal

- of gum forming constituents, without loss of desirable gasoline constituents.
2. Saving in cost of gum inhibitors, by eliminating the necessity therefor.
3. Improved antiknock properties.
4. No loss in the desired olefin or aromatic constituents.
5. Substantial reduction of sulfur impurities.
6. Improved susceptibility to, and permanence of tetra ethyl lead treatment.
7. Improved color stability.
8. Nearly total elimination of treating reagent and processing operation costs.
9. Recovery of gum and sulfur components in a non-corrosive utilizable form.
10. General applicability of refining method to widely varying raw gasolines whereby a product having a high induction period is readily and conveniently obtained.
11. According to one preferred embodiment of the present invention, petroleum hydrocarbon vapors of the gasoline boiling range are scrubbed continuously with a mobile liquid catalytic medium, for example, phosphoric acid, the temperature, time of contact and concentration of the acid being so adjusted with respect to each other as to convert substantially all of the gum forming and color imparting constituents and a large proportion of the sulfur impurities into materials of sufficiently higher boiling point as to separate completely by a slight dephlegmation under the conditions of the treatment without interfering with the progress of the refined gasoline vapor product. The vapors so treated are thereupon condensed and will be found to be stable both as to gum and color and have high induction period. In addition, the gasoline will be found to have an increased octane rating and require no further processing with the possible exception of the removal of hydrogen sulfide, which is effected completely either by a water or alkaline wash. By omitting the dephlegmation and especially if the scrubbing temperature is increased substantially, a considerable portion of the gum forming constituents are carried through and condensed with the gasoline vapors. However, they have been converted into the higher boiling form and can, therefore, be isolated readily by a simple distillation or rough fractional distillation.

The following comparative analyses of a gasoline before and after treatment are typical of the results obtainable by practicing our invention:

	Original	Treated
Gum value (cu. dish).....	599	2
Sulfur content (percent).....	.17	.09
Bromine unsaturation number.....	64.3	61.2
Octane number.....	66	68
Color.....	Yellow	Water white
Approximate yield.....		98%

We are aware that it has been proposed heretofore to treat various hydrocarbons with mixtures of phosphoric acid and sulfuric acid. However, we have found that under the conditions of our process in its preferred form sulfuric acid is rapidly decomposed. We are also aware that it has been proposed heretofore to pass hydrocarbon vapors in admixture with steam over a carrier sprayed with phosphoric acid (U. S. P. 1,709,315). However, such process is ineffective or only partially effective at best and must be supplemented by additional chemical treatments, such as, for example, a hypochlorite

treatment. Furthermore, the various acids of phosphorus have been considered ineffective in and of themselves for the purpose of refining raw gasoline (U. S. P. 1,914,953), and to the best of our knowledge the use of these acids has met with no commercial success in this field.

In contrast with the foregoing, the following examples illustrate specific procedures for applying the principles of our invention:

10

Example I

A commercial cracked gasoline was treated by flash distilling the raw gasoline at a rate of 200-300 c. c. per hour in such manner that throughout the run, vapors of substantially uniform composition were obtained which were at a temperature of approximately 175°-185° C. These vapors were introduced through a quarter inch tube into phosphoric acid of approximately 100% concentration and allowed to bubble upwardly through about 6 to 10 inches of the acid which was maintained at approximately 170°-180° C. by an oil bath that surrounded all except a small portion of the upper extremity of the catalyst containing vessel. Sufficient reflux was thus afforded in relation to the temperature, acid concentration, etc. to produce a clean separation of gum forming constituents and substantial separation of sulfur containing constituents in the form of a relatively high boiling polymer, which polymer was all retained in the catalyst containing vessel and in intimate admixture with the catalyst. This intimate mixture of polymer and catalyst was found to be at least as good a scrubbing medium for the purpose of our invention as the acid itself.

Following condensation of the scrubbed vapors, a light aqueous alkali wash was used to remove the traces of hydrogen sulfide. The following were the characteristics of the original and the treated gasoline:

	Original	Treated
Gum value, milligrams per 100 c. c. (copper dish).....	332	5
Sulfur content, per cent (damp method).....	0.16	0.07
Bromine unsaturation number (bromide-bromate reagent).....	63.9	61.2
Octane number.....	61	63
Absorption by sulfuric acid (unsaturated content).....	27.8	27.1
Color.....	Yellow	Water white
Approximate yield.....		99%

The oily polymer was formed in the phosphoric acid to the extent of about 1% of the weight of the gasoline treated. This polymer upon subsequent distillation at atmospheric pressure possessed a boil-range of 240°-330° C.; only a small undistilled residue remained. During operation of the process the polymer was disseminated throughout the acid in the form of tiny globules by the flow of gasoline vapors through the liquid mixture. Upon stopping the flow of vapors through the catalyst the liquid polymer rose rapidly to the surface of the acid and was thereupon separated from the acid by decantation in a substantially acid free condition. The acid layer was thus recovered practically quantitatively and in excellent condition for repeated use.

70

Example II

Substitute for the catalyst of Example I a phosphoric acid composition probably consisting of a mixture of ortho, pyro and possibly some meta phosphoric acid and which can be obtained by

75

dissolving approximately 7 or 8% of P_2O_5 in 100% H_3PO_4 . Otherwise, proceed as in Example I.

The product obtained under these conditions had a gum value of three milligrams per 100 c. c. and a bromine unsaturation number of 60.7. It is to be noted that although in this particular instance the gum value was slightly lower than that obtained in Example I with the same original gasoline, the bromine unsaturation number 10 was also lower.

As in the previously cited example, an oily polymer was produced, and separated by decantation from the acid.

Example III

Substitute for the catalyst of Example I a commercial phosphoric acid syrup of commerce which is of approximately 85% H_3PO_4 concentration. Otherwise proceed as in Example I.

The gasoline vapor passing through the acid during the first part of the run concentrated the acid as evidenced by the presence of water in the condensate. After equilibrium acid concentration conditions had been established as indicated by the absence of water in the condensate, and the fact that the condensate became clear, the condensed product was collected in a separate receiver and was found upon analysis to have substantially the same quality as the products of Examples I and II. Under the equilibrium conditions the acid was of a concentration less than 100% of H_3PO_4 although the concentration was considerably above 90% as measured by the water recovered in the gasoline condensate.

Example IV

A commercial cracked gasoline was treated in an all metal unit by feeding the vapors at the temperature as set forth in Example I through four one eighth inch orifices through an 8 inch depth of H_3PO_4 catalyst. The vapors were treated at a rate equal to 2,000-2,500 c. c. of raw gasoline liquid per hour; after passing through the catalyst, the vapors were introduced into a small diphlegmator or fractionating tower partly filled with packing for the purpose of removing the last traces of entrained and vaporized polymer. The reflux ratio to be effective for this purpose need be very small; frequently 2 to 5% is sufficient. From the top of the fractionating device the vapors were led to a condenser.

After a mild aqueous alkaline wash for hydrogen sulfide removal the condensed gasoline was found to have the following characteristics, which 55 by comparison with those of the original material further demonstrate the value of our process:

	Original	Treated
60 Gum value.....	179	4
Sulfur content (per cent).....	0.16	0.08
Octane value.....	66	68
Color.....	Yellow	Water white
Oxygen bomb stability (hours).....	1.5	8.75

We have found that nickel or nickel containing alloys, such, for example as Monel metal, are especially suited for the catalyst containing vessel. Moreover, the presence of the polymer has a distinct corrosion inhibiting effect on the metal. In lieu of nickel or its alloys, one may substitute other materials of construction, such as carbon, et al. It is to be understood that the temperature of the bath may be controlled by proper adjustment of the temperature of the entering gasoline vapors.

Example V

By increasing the gasoline vapor temperature and the catalyst temperature of Example IV thirty degrees centigrade or more and otherwise proceeding as in Example IV, a substantial portion of the polymer is carried over with the gasoline vapors.

The polymer so carried over was removed by increasing the reflux ratio in the fractionator. Alternatively, the treated vapors were condensed without refluxation and the condensate containing the polymer was given a simple distillation or rough fractionation to obtain a product comparable with that obtained in the preceding examples.

The catalyst is preferably a liquid under the conditions of the treatment and is preferably substantially insoluble in the polymer that is formed and with which it is in intimate mixture while in use. Inasmuch as the catalyst is immiscible, it separates from the polymer upon standing and may be recovered as by decantation and returned to the process. In this way the catalyst may be used indefinitely as there is no perceptible loss except that attributable to usual mechanical losses incident to the handling of any material.

While ortho phosphoric acid is admirably suited for the purpose of our process, in that it not only effects substantially complete conversion of the gum forming constituents into separable form, but in addition attains the other desirable objectives of the present invention, nevertheless other catalytic compositions may be substituted therefor. Thus, for example, a mixture of the pyro and ortho phosphoric acids may be employed, or alternatively a mixture of the meta, pyro and ortho phosphoric acids. In lieu of phosphoric acids the corresponding phosphorous, and hypophosphorous acids may be substituted in whole or in part for the phosphoric acids. In the case of the acids of lower state of oxidation there is evidence that the materials react, at least in part, to form the more stable phosphoric acid with attending formation of phosphine.

In addition to the oxygen acids of phosphorus, one may use the acid salts to replace the free acid in whole or in part. Similarly one may substitute the alkyl or aryl acid esters, which evidently likewise undergo some chemical change in the course of their use, but as in the other instances, the reaction products are themselves catalytically active.

While from the standpoint of availability, the oxygen acids of phosphorus and their derivatives 55 are especially suitable, we may use other known non-reducible acids of phosphorus, such, for example, as the sulfur containing acids of phosphorus or the sulfur and oxygen containing acids of phosphorus, as for example, the thio phosphoric acid H_3PSO_3 , or dithiophosphoric acid.

The catalyst may be made in various ways, for example, one may use ordinary phosphoric acid syrup of commerce, which is approximately 85% H_3PO_4 . However, if desired, one may use 100% H_3PO_4 by adding sufficient P_2O_5 to the phosphoric acid syrup of commerce to combine with the free water. An excess of P_2O_5 may be added to the phosphoric acid syrup over and above that required to react with all of the water to form 100% H_3PO_4 , in which case one obtains a mixture of the pyro and ortho phosphoric acid, or depending upon the amount of P_2O_5 added, a mixture of all three of the phosphoric acids. Instead of add- 75

ing P_2O_5 to the commercial phosphoric acid, one may add P_2O_3 .

The composition of the starting catalytic material may be varied considerably inasmuch as it undergoes some change with use in attaining an equilibrium. This is particularly true with respect to the water content of the catalytic composition.

While we prefer to use a fluid catalytic composition which is immiscible with the polymer, whereby it may be separated from the accumulated polymer by stratification and decantation, it is to be understood that the catalyst can be present as a solid, in which case it may be suspended or dispersed in the polymer or some other fluid inert vehicle.

A further modification of the catalytic composition consists in the use of catalytically active salts either alone or in admixture with the free acids which salts exert desirable catalytic influences. Such effect is produced by the addition of salts of catalytically active metals, such as copper, nickel, cadmium, zinc, cobalt, chromium, iron and other heavy metals. For this purpose one may add a small amount of a salt as for example a phosphate, of the metal to the fluid acid catalyst or one may incorporate a small amount of oxide directly to the acid, in which case the oxide probably combines with the acid to form the salt in situ. The effect of the addition of the salts is to reduce the temperature of the reaction or the required time of contact, and to some extent in changing the nature of the hydrocarbons being treated as to improve substantially the antiknock value, while at the same time eliminating gum forming constituents, sulfur and the like. The amount of the catalytically active metal or salt which is used may vary from a fraction of a per cent up to several per cent, in general, we prefer to restrict the amount of salts insofar as this is necessary to preserve the fluidity of the scrubbing media.

We have found that certain advantages are obtained by effecting the reaction within a comparatively narrow range of temperature which depends to some extent on the nature of the gasoline, although it is possible to gain many of the advantages of our invention over a comparatively wide range of temperature. In general, the temperature should be sufficiently high with respect to the time and conditions of contact between the vapor and the scrubbing medium, to convert the gum forming constituents into a physically separable form and preferably without inducing substantial condensation of the gasoline vapors. On the other hand, the upper limit is preferably below that temperature at which objectionable amounts of the polymer are carried by the petroleum vapors out of the treating system; otherwise it may become necessary to redistill the product to remove the gum which has been converted into relatively high boiling polymer and is therefore physically separable from the gasoline, but, because of the high temperature of the treatment at which it has an appreciable partial pressure, the polymer has been carried through the treating system into the distillate.

We have found it desirable in operating our process to reflux or dephlegmate the vapors after treatment with the scrubbing fluid in order to obtain a good and complete separation of the gum forming polymer from the desired refined gasoline vapors. In general, this separation is not difficult and only a very small amount of

fractionation or dephlegmation is necessary to give a very clean separation. Under closely controlled scrubbing conditions in the catalytic treatment little, if any, dephlegmation or fractionation is necessary, but in the interest of safety and smooth operation, a dephlegmating or fractionating operation is advantageous.

The manner of contacting or scrubbing the vapors of the gasoline with the scrubbing fluid is not critical. In general, any known equipment for effecting contact between a vapor and a liquid, may be used. A very convenient procedure consists in bubbling the vapors through a pool of the catalyst, which, of course, consists of a mixture of acid and immiscible polymer. Another method of effecting the scrubbing operation consists in spraying the liquid catalytic composition through a tower in countercurrent or parallel direction with respect to the gasoline vapors being treated. If desired, such tower may be filled with a packing, over which the liquid flows downwardly and is then recirculated.

To remove the polymer, the scrubbing medium is withdrawn continuously or periodically, permitted to stratify, whereby polymer arises to the surface and the acid settles to the bottom, after which the acid is returned to the system and the polymer is subjected to recracking or used for other purposes, preferably after washing with water to remove water soluble constituents.

We have found that in general the presence of substantial amounts of water interferes with the effective and complete separation of the gum forming constituents from the desired gasoline constituents. However, special precautions for the removal of water are unnecessary inasmuch as amounts of water such as are commonly dissolved in gasoline are not objectionable.

In line with the foregoing, we have found that when a catalytic composition is employed which contains a substantial amount of water, the hydrocarbon vapors passing through the acid catalyst tend to dehydrate the acid until an equilibrium is attained. As the state of equilibrium is approached, the quality of the gasoline condensate improves insofar as its gum content is concerned. Thus, if one starts a process with the 85% phosphoric acid, the acid is concentrated until it reaches a concentration of approximately 90-92% or even higher H_3PO_4 , depending upon the temperature of the scrubbing operation. The equilibrium is established rapidly and the gasoline required to establish this equilibrium may after decantation of the water be reprocessed. As soon as the equilibrium is established the catalyst is satisfactory for continued use. This method of obtaining a catalytic composition is in general more convenient and economical than a procedure which involves the procurement and addition of P_2O_5 to commercial phosphoric acid syrup.

The gasoline condensate obtained after scrubbing the raw gasoline with the catalytic scrubbing medium usually contains a small amount of dissolved hydrogen sulfide, which is probably present in the original raw gasoline. This is removed conveniently by contacting the vapors with lime, or washing the condensed gasoline with a small amount of water or an aqueous alkaline solution of soda ash or alkali. This treatment to remove hydrogen sulfide does not in any way change the motor fuel value of the condensate, but serves the function of reducing the odor and corrosion tendency of the gasoline product. After

the alkali wash a water white gasoline is obtained which has all of the properties described heretofore.

We have also found that instead of suspending the catalytical active solid material in a mobile or liquid medium which is substantially non-volatile under the conditions of our process, the catalyst may be used in the form of a solid either as such, or when deposited on a solid carrier.

10 To illustrate the principles of the application of our invention to a process in which the gasoline is in vapor state and the catalyst is solid:

A commercial cracked gasoline was treated by distilling the raw gasoline at a rate of 200-300 15 c. c. per hour in such manner that throughout the run, vapors of substantially uniform composition were obtained. The temperature of the stream of vapors was adjusted at 225°-240° C. and subsequently the vapors were passed through 20 a tube or tower filled with granules of pumice which was saturated with phosphoric acid. The temperature of the tower was maintained at approximately the temperature of the vapors entering the tower. Under these conditions most 25 of the polymer was carried from the tower into a fractionating column where the temperature was adjusted to condense 3 or 4 per cent of the product. The condensate so collected consisted predominantly of the reacted gum forming constituents in the form of a mobile liquid which 30 was high in sulphur. The vapors from the fractionating column were condensed and were found to be of excellent gasoline fuel quality.

The tower consisted of a two inch tube approximately thirty inches long which was lagged and electrically heated to maintain the desired temperature conditions.

In lieu of the pumice granules there were substituted granular pellets of clay made by mixing 40 clay with approximately 25 per cent by weight of 85 per cent phosphoric acid and sufficient water to produce a moldable mix. The mix was formed into pellets and dried at 105° C., after which it was packed in the tower.

45 Other carriers may be used, such for example as a moldable mixture of sodium meta phosphate and phosphoric acid together with activated carbon or other absorbent forms of carbonaceous materials capable of holding the phosphoric acid.

50 Coal, coke, peat and cellulosic materials may be substituted for the activated carbon to form a solid carrier for the active component.

As a modification of the foregoing procedure, the condensate from the fractionating column 55 was delivered to the top of the catalyst tower. In this case the gasoline vapors were caused to flow upwardly in counter-current direction in respect to the mobile liquid polymer which drained over the solid catalyst and was collected 60 at the bottom of the tower. As a further modification, by reducing the temperature of the tower, it was possible to condense the polymer in a mobile liquid form, as formed in the tower without condensing the desired gasoline vapors 65 which were condensed and collected separately.

In this specification we referred to the undesirable constituents of the gasoline, which are separated by our process, as "gum forming constituents" and in the catalyzed form these constituents have been referred to sometimes as 70 "polymers". While we believe that the material separated, is in fact the gum producing fraction of the raw gasoline in the form of a polymer that includes sulphur impurities of the raw gasoline, 75 probably in the form of a reaction product of

some sort or other, it is to be understood that our invention is not limited by any theory to explain the effects. Similarly, while we refer to the process as a catalytic process (in view of the fact that there appears to be no perceptible consumption in the acid reacting phosphorus reagent), it is to be understood that we are not in a position at this time to classify the nature of the reactions which contribute to the success of our process.

Under the preferred conditions of operation the Engler distillation characteristics of the raw gasoline are not changed substantially. Nevertheless, in view of the relatively wide range of 10 temperature condition which can be used without departing from the scope of our invention, as well as the fact that chemical changes additional to those incident to gum removal may take place, especially as the reaction temperature approaches cracking temperatures, we do not limit 15 ourselves to a product whose Engler distilling characteristics are exactly reproduced in the final product.

In general, we prefer to operate below cracking temperatures, that is, temperatures such as 20 are commonly used in the art today in converting relatively high boiling hydrocarbons to those of gasoline boiling range.

One of the distinct advantages of our process reside in the fact that widely varying raw cracked 25 gasoline distillates may be treated without necessitating extensive changes in the treating conditions, such as temperature, time of contact, etc. Nevertheless, under some conditions successive treatments such as might be had by subjecting the gasoline to two catalytic operations 30 in series or by recycling the stock in a batch-wise manner, fall within the purview of our invention.

We have found it convenient in preparing the 35 catalyst to dissolve or suspend P_2O_5 in phosphoric acid of commerce which acid usually contains about 15% water. By adding sufficient P_2O_5 the ortho phosphoric acid is probably converted to pyro phosphoric acid and perhaps to 40 meta phosphoric acid. If desired one can add sufficient P_2O_5 to retain a portion thereof in unreacted form. As a rule there is sufficient water in the gasoline to combine with such P_2O_5 especially after a long period of treatment, even 45 though the amount of water dissolved in a decanted raw gasoline is very small. One of the 50 advantages of the present invention resides in the fact that the reacted P_2O_5 product is itself an excellent catalyst for the purpose of our 55 invention.

Although we have described the principles of our invention and have set forth specific embodiments of the application thereof, it is to be understood that these are illustrative only and 60 that the invention is not restricted to the temperatures, concentrations, etc., specifically set forth. Further, it is to be understood that our process may be operated continuously or otherwise, and at subatmospheric pressure as well as 65 super-atmospheric pressure, if so desired.

What we claim is:

1. In a process of treating a cracked hydrocarbon fraction of gasoline motor fuel boiling range containing objectionable gum-forming constituents wherein the gum-forming constituents are converted into reaction products which are of sufficiently low vapor pressure to render them 70 separable from the said cracked hydrocarbon fraction by reason of the difference in vapor pres- 75

sure by contacting vapors of the said cracked hydrocarbon fraction with a catalyst, the step of effecting conversion of gum-forming constituents and separation of the reaction products which comprises bubbling the vapors of substantially anhydrous cracked hydrocarbons of gasoline motor fuel boiling range through a liquid body comprising an acid of phosphorous at a temperature sufficiently high to avoid substantial condensation of the cracked hydrocarbons and below the temperature at which any appreciable amount of the reaction product is vaporized.

2. In a process of treating cracked hydrocarbons of gasoline motor fuel boiling range containing objectionable gum-forming constituents wherein the gum-forming constituents are converted into reaction products which are of sufficiently low vapor pressure to render them separable from the said hydrocarbons by reason of the difference in vapor pressure by contacting the vapors of the said hydrocarbon with a catalyst, the step of effecting conversion of gum-forming constituents and separation of the reaction products which comprises bubbling the vapors of substantially anhydrous hydrocarbons of gasoline motor fuel boiling range through a liquid body comprising phosphoric acid at a temperature sufficiently high to avoid substantial condensation of the said hydrocarbons and below the temperature at which any appreciable amount of the reaction product is vaporized.

3. In a process of treating a cracked hydrocarbon fraction of gasoline motor fuel boiling range containing objectionable gum-forming constituents wherein the gum-forming constituents are converted into reaction products which are of sufficiently low vapor pressure to render them separable from the said cracked hydrocarbon fractions by reason of the difference in vapor pressure by contacting vapors of the said cracked hydrocarbon fraction with a catalyst, the step of effecting conversion of gum-forming constituents and separation of the reaction products which comprises bubbling the vapors of substantially anhydrous cracked hydrocarbons of gasoline motor fuel boiling range through a liquid body comprising a mixture of an acid of phosphorus and reaction products at a temperature sufficiently high to avoid substantial condensation of the cracked hydrocarbons and below the temperature at which any appreciable amount of the reaction products is vaporized.

4. In a process of treating a cracked hydrocarbon fraction of gasoline motor fuel boiling range containing objectionable gum-forming constituents wherein the gum-forming constituents are converted into reaction products which are of sufficiently low vapor pressure to render them separable from the said cracked hydrocarbon fraction by reason of the difference in vapor pressure by contacting vapors of the said cracked hydrocarbon fraction with a catalyst, the step of effecting conversion of gum-forming constituents and separation of the reaction products which comprises bubbling the vapors of a substantially anhydrous cracked hydrocarbon of gasoline motor fuel-boiling range through a liquid body comprising an acid of phosphorus at a temperature between 170° and 240° C.

70 5. In a process of treating a cracked hydrocar-

bon fraction of gasoline motor fuel boiling range containing objectionable gum-forming constituents wherein the gum-forming constituents are converted into reaction products which are of sufficiently low vapor pressure to render them separable from the said cracked hydrocarbon fraction by reason of the difference in vapor pressure by contacting vapors of the said cracked hydrocarbon fraction with a catalyst, the steps of effecting conversion of gum-forming constituents and separation of the reaction products which comprises bubbling the vapors of substantially anhydrous cracked hydrocarbons of gasoline motor fuel boiling range through a liquid body comprising the mixture of an acid of phosphorus and reaction products at a temperature between 170° and 240° C., withdrawing a portion of the liquid catalyst body, separating therefrom reaction products and returning the purified catalyst to the said catalyst body.

20 6. The process of treating hydrocarbons of gasoline motor fuel boiling range to remove gum forming constituents therefrom comprising passing vapor of the said hydrocarbons substantially free of steam at a temperature between 175° C. and 185° C. in contact with a catalyst comprising an acid of phosphorus that is substantially non-volatile at the temperature of the treatment whereby the treated gasoline is rendered substantially free of gum forming constituents and the reacted gum forming constituents are caused to remain with the catalyst by reason of the relatively high boiling point thereof as compared with the temperature of the treatment.

25 7. The process of treating hydrocarbons of gasoline motor fuel boiling range to remove gum forming constituents therefrom comprising contacting vapor of the said hydrocarbons substantially free of steam at a temperature between 175° C. and 185° C. with a liquid catalyst body comprising an acid of phosphorus that is substantially non-volatile at the temperature of the treatment whereby the treated gasoline is rendered substantially free of gum forming constituents and the reacted gum forming constituents are caused to remain in the catalyst body by reason of the relatively high boiling point thereof as compared with the temperature of the treatment.

30 8. The process of treating hydrocarbons of gasoline motor fuel boiling range to remove gum forming constituents therefrom comprising contacting vapor of the said hydrocarbons substantially free of steam at a temperature between 175° C. and 185° C. with a liquid catalyst body comprising an acid of phosphorus that is substantially non-volatile at the temperature of the treatment in a reaction zone, whereby reacted gum forming constituents are deposited in the catalyst body by reason of the relatively high boiling point thereof as compared with the temperature of the treatment, withdrawing a portion of said catalyst from the reaction zone, separating therefrom reacted gum forming constituents, returning the purified catalyst to the reaction zone and separately withdrawing treated gasoline substantially free of gum forming constituents from the reaction zone.
